ARC LAMP OR THE LIKE

Richard C. Beitz, Amherst, N. Y., assignor to
 American Optical Company, Southbridge,
 Mass., a voluntary association of Massachusetts

Application July 21, 1950, Serial No. 175,058

6 Claims. (Cl. 314—71)

1

This invention relates to arc lamps, welding apparatus and the like wherein one or more movable electrodes or the like are employed, and more particularly to electrical and mechanical means for automatically moving such electrode or electrodes for automatically effecting an arc and for adjusting the arc to a proper predetermined size when the apparatus is placed in operation, as well as for automatically advancing said electrode or electrodes thereafter toward the arc when required for maintaining said arc at a substantially constant size as the electrode or electrodes are consumed during use.

While the invention is especially useful in arc lamps which are to be used with photomicrographic apparatus wherein a substantially constant high intensity light source is needed and wherein freedom from vibration during photographing and such, particularly at extremely high magnifications, is essential, it nevertheless has general utility for controlling the size of arc in projectors, welding apparatus, electric arc furnaces and the like. Accordingly, hereinafter when the words electrode or electrodes are used, it should be kept in mind that they are intended to apply to the electrically conductive arc sustaining members or materials ordinarily encountered in such apparatus. The apparatus of the present invention is of such construction and arrangement that it may be, by the mere pressing of a switch, alternatively used on A. C. or D. C. current. Also the operating mechanism of the present invention is of such high sensitivity that when the same is being used in an arc lamp, no appreciable visible change in intensity of the arc will be noticeable during ordinary use thereof.

It is, accordingly, an object of the present invention to provide in an arc lamp or like apparatus efficient, highly sensitive and inexpensive means for gripping and guiding an electrode or a pair of electrodes and for automatically moving the same so as to establish an arc, so as to immediately thereafter automatically adjust the arc to proper predetermined size and so as to maintain the arc substantially constant during continued use thereof.

It is an additional object of the invention to provide in an arc lamp or like apparatus automatically operable means of the type described which may be readily operated on alternating or direct current, as desired, while still retaining the high degree of sensitivity desired.

It is, also, an object of the invention to provide in apparatus of the character described, readily adjustable means for altering the prede-

termined size of arc which is to be automatically maintained during operation of the apparatus.

Other objects and advantages of the invention will become apparent from the detailed description which follows when taken in conjunction with the accompanying drawing in which:

The single diagrammatic figure thereof indicates parts of an arc lamp or the like and the electrical and mechanical means for operating same.

Referring to the drawing in detail, there is shown at 12 and 14, respectively, a pair of electrodes or carbons which may serve to establish and maintain an arc of suitable size at a point 16 in an arc lamp or the like. Mechanism for advancing these electrodes toward each other is diagrammatically shown herein and comprises suitable means for attaching the electrodes to a pair of endless chains or belts 15 and 17, which are caused to move in opposite directions for advancing the electrodes. The belts 15 and 17 are actuated by means of a pair of shafts 18 and 19 geared together by means of gears 20 and 22. In the drawing, electrode 14 is shown as somewhat thicker in diameter than electrode 12 and gear 22 is of greater size than gear 20 for the purpose of obtaining the proper rate of advance of the electrodes as they are consumed. While the apparatus will be first described for use with D. C. current, it should be noted that in cases where an A. C. current is to be employed for operation of the arc, electrodes of different sizes might be employed instead of the ones shown. Gear 22 is actuated by shaft 19 which is in turn driven by reduction gear means 24 driven by a motor 26. In a preferred construction, means 24 and motor 26 may be suitably incorporated in a unitary electric motor housing with gear means 24 having a speed reduction ratio in the neighborhood of 60 to 1. While endless belts have been shown in the drawing to move the electrodes, it will be obvious that grooved pressure rollers could be arranged, as is well known in the art, to move the electrodes 12 and 14.

The electrode 12 is connected by suitable means to a main electrical conductor 28 while electrode 14 is connected to a terminal of a three-way separable connector 30 and then at 32 is connected to one end of a heavy-duty ballast resistor 34. The opposite end 35 of the ballast resistor is in turn connected to another terminal of separable connector 30 and then to a second main electrical conductor 36, so that external electric current may be supplied to the apparatus by means of conductors 28 and 36. The reason for using a

separable connector at 30, especially when the mechanism is to be incorporated in an arc lamp or projector, is to allow all parts of the structure diagrammatically shown except ballast resistor 34 to be housed within the arc lamp housing, the ballast resistor being placed a short distance from said arc lamp since the same is bulky and generates considerable heat and might be at times otherwise objectionable.

The motor 26 is arranged to control the movement of the electrodes 12 and 14 and is of a construction embodying a reversible rotatable armature 38 and a pair of field coils 40 and 42, with one terminal of the armature and of each field coil connected together at a common point. Such a motor is often referred to as a split-field series type motor since the two field coils thereof act in opposition to each other in accordance with the current flowing therethrough and through the armature and the direction of operation of the motor accordingly depends upon which field coil magnetic flux dominates. In the present invention, the opposite free terminal of the field coil 40 is connected to a resistor 44, of suitable electrical characteristics, which in turn is connected to main conductor 28. The opposite free terminal of the other field coil 42 is in turn connected to a suitable fixed resistor 46 of suitable electrical characteristics which in turn is connected to an adjustable resistor 48 and this resistor in turn is connected to main conductor 36. The opposite free terminal of the armature 38 is connected through the separable connector 30 preferably to an intermediate point 50 on ballast resistor 34 adjacent the end 32 of the resistor to which electrode 14 is connected or even at this end as determined by the operative characteristics of the control circuit and the mechanical characteristics of the arc lamp as will be presently described.

It will be noted that the electrical system just described is in effect a Wheatstone bridge circuit in which two arms of the bridge extending from point 56 common with conductor 28 through the electrodes 12 and 14 and ballast resistor 34 to point 58 common with conductor 36 constitute a primary circuit 54, with the point 50 common to these two arms. The other two arms of this Wheatstone bridge are formed by field coil 40 and resistor 44 and by the field coil 42 and resistors 46 and 48, respectively, and together constitute a secondary circuit 60. The common point previously referred to and to which one armature terminal is connected is indicated at 62, while the opposite armature terminal thereof is connected to point 50, and preferably intermediate the armature and point 62 a normally-closed precision snap-action switch 63 or the like is connected.

The Wheatstone bridge control circuit just described operates in the following manner. Assuming that the lamp is to be operated on D. C. current and that the electrodes are in spaced relation at the time it is to be placed in operation by connecting the conductors to this source of power, the electric current being supplied will flow from point 58 mainly through ballast resistor 34 to point 50 and then through armature 38 and switch 63 to point 62. Only a negligible amount of current will pass through resistors 46 and 48 and field coil 42 to point 62 due to the high impedance and resistance thereof as compared with that through the armature and ballast. Current from point 62 will pass through field coil 40 and resistor 44 to point 56. When

such flow of current occurs motor 26 will be energized to operate the drive mechanism for the electrodes in a forwardly direction thereby advancing the electrodes toward point 16 and this advance will be rapid since the current flow through the armature at this time will be comparatively large. This forward travel will continue until contact between the electrodes is established.

Immediately thereafter the resistance through the electrode containing arm of the bridge will drop, thereby allowing nearly all or the greater part of the main line voltage to be developed across the part of the ballast between points 35 and 58. Accordingly, only negligible current will flow at such time through the arm of the bridge containing field coil 40 because of the high impedance and resistance therein. Thus coil 42 and armature 38 will be subjected to the main line voltage, thereby energizing motor 26 to operate in the opposite direction. This will cause the electrodes 12 and 14 to move apart until the resistance in the electrode containing arm of the bridge including the resistance across the arc at 16 builds up to such a point that the bridge circuit is substantially in balance, with the potentials at points 50 and 62 substantially equal. Of course, mechanical friction and such will always be present and will tend to prevent the motor from retracting the electrodes all the way to provide a perfectly balanced bridge. Consequently, the armature will remain stationary while the electrodes burn back to and sufficiently beyond this balanced condition so as to increase the voltage drop in this arm of the bridge relative to that in the arm between points 50 and 58 and thus produce an out-of-balance condition of sufficient magnitude to cause field coil 40 to be energized more strongly than field coil 42. This condition will cause armature 38 to rotate in a forward direction at a very low rate of speed, particularly when a reduction gear unit with a ratio of approximately 60 to 1 is provided in the driving system for shaft 19, and in a more or less continuous manner.

The forward rotation of the armature to advance the electrodes or carbons will not always be of a uniform rate; since certain conditions, such as hard and soft spots in the carbons, may cause the carbons at times to burn away at varying rates. However, when these variations occur, the speed of the motor will change in such a way as to maintain the current through the ballast and the electrodes at a substantially constant value, which is synonymous with keeping the ratio of the voltage drops across the ballast resistor and across the carbons at a substantially constant value.

It will be noted that the armature is connected at the intermediate point 50 in the ballast resistor instead of being connected at the end 32. The purpose for this is to provide at all times a certain small amount of resistance in the arm of the bridge containing the electrodes and between points 50 and 56, thereby giving greater driving torque in the forward direction of rotation of the motor than in the reverse direction. Also frictional resistance in the operating parts of the driving mechanism and such will combine with the torque so provided in such a manner that the electrodes will not be moved quite as far apart as they would have been had the armature connection been made at point 32. Thus the carbons will burn off somewhat after the arm is "struck" and before the motor

26 becomes operative to move the electrodes forwardly, and thereafter the motor will always tend to drive in a forwardly direction; thus preventing "hunting" which might otherwise result when a more evenly balanced bridge condition exists.

The ratio of the resistance in the secondary circuit 60 as compared to the primary circuit 54 may be varied slightly by adjustment of the relatively light weight resistor 48 and this control may be used to vary within desired limits the normal spacing which is to be maintained at gap 16 during normal operation of the apparatus. In fact resistance 48 could be placed in either arm of the secondary circuit 60 and could be readily arranged to provide the control desired.

When the lamp is to be used with alternating current, electrodes of equal diameter may be substituted in place of electrodes 12 and 14. The only other change needed for operation on A. C. current then would be either the omission of resistors 44 and 46 from the secondary circuit 60 of the bridge or if desired, and as shown in the drawing, the resistance 44 and 46 could be in effect eliminated by the closing of switches 64 and 66 for short circuiting the resistors. In fact, such might be accomplished, as is obvious, by the mere use of a single double-pole switch controlling both resistances at the same time.

The normally closed switch 63 in the armature circuit is so positioned that it may be actuated by a cam 68, when the electrode 12 has been substantially consumed, for interrupting the current flow through the armature 38 and thereby preventing further forward movement of the driving mechanism. For convenience during operation of the lamp, there is provided a normally open switch 70 arranged in series with a pilot light 72 and connected to points 50 and 56, which will be energized when switch 70 is closed and this switch is preferably so positioned relative to cam 68 and switch 63 that shortly prior to the end of the operating stroke of the mechanism a warning signal will be given by the pilot light so the operator may replace the carbons before attempting to use the lamp for any appreciable period of time thereafter. Such has been found to be useful particularly in photomicrographic work requiring exposures of appreciable duration, thus avoiding undesired interruption of the arc during such photographing of specimens and the like. While opposed movable electrodes are shown and described above, it will be understood that, when desired, only one electrode need be movable for utilizing the automatic control means disclosed.

Having described my invention, I claim:

1. In an apparatus of the character described, the combination of a pair of electrodes for establishing and sustaining an arc therebetween, a ballast resistor having one end thereof connected to one of said electrodes, a pair of main conductors, respectively, so as to provide a secondary electrodes and to the opposite end of said ballast resistor, respectively, so as to place same in series relation in a primary circuit, gripping and guiding means constructed and arranged so as to move at least one of said electrodes toward and away from the other when actuated, driving means including a rotatable electric motor for actuating said gripping and guiding means, said motor having a pair of field coils and an armature with a lead from each connected together at a common point, said field coils being arranged in said motor in opposed relation to each other.

so as to tend to rotate said motor in opposite directions when energized, means for connecting the opposite leads of said field coils to said main conductors connected to the other of said secondary circuit therebetween, and means for connecting the other lead of said armature to said primary circuit at a point adjacent the connection of said one electrode to said ballast resistor.

2. In an apparatus of the character described, 10 the combination of a pair of electrodes for establishing and sustaining an arc therebetween, a ballast resistor having one end thereof connected to one of said electrodes, a pair of main conductors connected to the other of said electrodes and to the opposite end of said ballast resistor, respectively, so as to place same in series relation in a primary circuit, gripping and guiding means constructed and arranged so as to move at least one of said electrodes toward and away from the other when actuated, driving means including a rotatable electric motor for actuating said gripping and guiding means, said motor having a pair of field coils and an armature with a lead from each connected together at a common point, said field coils being arranged in said motor in opposed relation to each other so as to tend to rotate said motor in opposite directions when energized, means for connecting the opposite leads of said field coils to said main conductors, respectively, so as to provide a secondary circuit therebetween, and means for connecting the other lead of said armature to said ballast resistor at a point intermediate the ends thereof.

3. In an apparatus of the character described, 35 the combination of a pair of electrodes for establishing and sustaining an arc therebetween, a ballast resistor having one end thereof connected to one of said electrodes, a pair of main conductors connected to the other of said electrodes and to the opposite end of said ballast resistor, respectively, so as to place same in series relation in a primary circuit, gripping and guiding means constructed and arranged so as to move at least one of said electrodes toward and away from the other when actuated, driving means including a rotatable electric motor for actuating said gripping and guiding means, said motor having a pair of field coils and an armature with a lead from each connected together at a common point, said field coils being arranged in said motor in opposed relation to each other so as to tend to rotate said motor in opposite directions when energized, means for connecting the opposite leads of said field coils to said main conductors, respectively, so as to provide a secondary circuit therebetween, said last mentioned means including a readily adjustable resistor in series relation in said secondary circuit for controlling the normal spacing of said electrodes during the operation thereof, and means for connecting the other lead of said armature to said primary circuit at a point adjacent the connection of said one electrode to said ballast resistor.

4. In an apparatus of the character described, 65 the combination of a pair of electrodes for establishing and sustaining an arc therebetween, a ballast resistor having one end thereof connected to one of said electrodes, a pair of main conductors connected to the other of said electrodes and to the opposite end of said ballast resistor, respectively, so as to place same in series relation in a primary circuit, gripping and guiding means constructed and arranged so as to move at least one of said electrodes toward and away from the other when actuated, driving

means including a rotatable electric motor for actuating said gripping and guiding means, said motor having a pair of field coils and an armature with a lead from each connected together at a common point, said field coils being arranged in said motor in opposed relation to each other so as to tend to rotate said motor in opposite directions when energized, means for connecting the opposite leads of said field coils to said main conductors, respectively, so as to provide a secondary circuit therebetween, said last mentioned means including a readily adjustable resistor in series relation in said secondary circuit for controlling the normal spacing of said electrodes during the operation thereof, and means for connecting the other lead of said armature to said ballast resistor at a point intermediate the ends thereof.

5. In apparatus of the character described and adapted to operate selectively upon alternating or direct current, the combination of a pair of electrodes for establishing and sustaining an arc therebetween, a ballast resistor having one end thereof connected to one of said electrodes, a pair of main conductors connected to the other of said electrodes and to the opposite end of said ballast resistor, respectively, so as to place same in series relation in a primary circuit, gripping and guiding means constructed and arranged so as to move at least one of said electrodes toward and away from the other when actuated, driving means including a rotatable electric motor for actuating said gripping and guiding means, said motor having a pair of field coils and an armature with a lead from each connected together at a common point, said field coils being arranged in said motor in opposed relation to each other so as to tend to rotate said motor in opposite directions when energized, means for connecting the opposite leads of said field coils to said main conductors, respectively, for operation on direct current, said last mentioned means including a resistor of predetermined value in series relation with each field coil thereby providing a secondary circuit between said conductors which includes said common point, readily operable switch means connected across each resistor and operable to eliminate the effect of said resistors in said secondary circuit when it is desired to operate said apparatus on alternating current, and means connecting the other lead of said armature to said primary circuit at a point adjacent the connection of said one electrode to said ballast resistor.

6. In apparatus of the character described and adapted to operate selectively upon alternating or direct current, the combination of a pair of electrodes for establishing and sustaining an arc therebetween, a ballast resistor having one end thereof connected to one of said electrodes, a pair of main conductors connected to the other of said electrodes and to the opposite end of said ballast resistor, respectively, so as to place same in series relation in a primary circuit, gripping and guiding means constructed and arranged so as to move at least one of said electrodes toward and away from the other when actuated, driving means including a rotatable electric motor for actuating said gripping and guiding means, said motor having a pair of field coils and an armature with a lead from each connected together at a common point, said field coils being arranged in said motor in opposed relation to each other so as to tend to rotate said motor in opposite directions when energized, means for connecting the opposite leads of said field coils to said main conductors, respectively, for operation on direct current, said last mentioned means including a resistor of predetermined value in series relation with each field coil thereby providing a secondary circuit between said conductors which includes said common point, readily operable switch means connected across each resistor and operable to eliminate the effect of said resistors in said secondary circuit when it is desired to operate said apparatus on alternating current, said secondary circuit also including a readily adjustable resistor for controlling the normal spacing of said electrodes during the operation thereof, and means for connecting the other lead of said armature to said primary circuit at a point adjacent the connection of said one electrode to said ballast resistor.
